MAXIMILIAN CHARLES SCHWEINERT, OF WEST HOBOKEN, AND HENRY P. KRAFT,
OF RIDGEWOOD, NEW JERSEY.

TIRE-VALVE.

1,266,501.

Specification of Letters Patent. Patented Jan. 25, 1921.

Application filed August 27, 1915. Serial No. 47,604.

To all whom it may concern:

Be it known that we, MAXIMILIAN CHARLES SCHWEINERT, of West Hoboken, in the county of Hudson and State of New Jersey, and HENRY P. KRAFT, of Ridgewood, in the county of Bergen and State of New Jersey, both citizens of the United States of America, have invented certain new and useful Improvements in Tire-Valves, of which the following is a specification.

This invention relates to improvements in valves of the type used for inflating pneumatic tires. Specifically it is directed to an improved method of constructing the movable valve member of the well-known Schrader valve. In this construction the valve proper, which is adapted to coact with a seat carried by or formed in the valve shell or casing, is mounted upon a pin or carrier the upper part of which pin extends to near the top of the valve shell for the purpose of deflating, and the lower part of which extends through the loading spring and forms a carrier for the latter. Both the upper and lower parts of the pin serve as guides to maintain the valve in proper alignment. In tire valves or the like the valve proper and its pin are necessarily exceedingly small, the total length being slightly over an inch, and the diameter of the pin and valve proper being correspondingly reduced. The valve proper is in the form of a cup which must be rigidly joined to the pin, preferably with a leak-tight joint, and difficulty has been encountered in the past in producing such a connection having in view the extreme cheapness of the structure, the small dimensions of the parts, and the necessity of assembling them in a commercial manner.

According to the present invention a construction is provided in which the cup and pin are connected with a leak-tight joint in a simple and expeditious manner, and at the same time the connection is made permanent and rigid so that the parts cannot slip in use.

Referring to the drawings,

Figure 1 is an elevation on a greatly enlarged scale of a valve proper and pin embodying the invention.

Fig. 2 is a view of the pin before the valve cup is applied.

Fig. 3 is an elevation of the valve proper, with its seat and plug. 55

Referring to the drawings, let A indicate the valve cup which is designed to carry a circular packing B which is adapted to make contact with a suitable seat shown at S in Fig. 3, which is held in the valve shell 60 by screw-threaded plug P. The cup A is provided with a central bore A' through which extends a pin C. The pin is initially formed with a swaged up portion D which serves when the parts are in position as a holding shoulder or flange to prevent the packing B from moving out of the cup during the act of opening the valve.

Referring to Fig. 2 which shows the shape of the pin before the valve cup is applied, it will be noted that the upper portion a of the pin above the shoulder D is of general cylindrical form and may be of any suitable diameter. Preferably the pin is formed from commercial wire and the diameter of 75 the portion a will be that of the wire. Below the shoulder D is a seating portion b which is of such diameter as to make a frictional or jamming fit with the bore A' of the cup A. The length of the portion b is 80 somewhat greater than the length of the cup, and below this portion is a portion c of less diameter than the portion b, the two diameters being preferably joined or connected by a tapered portion d. The pin as 85 shown in Fig. 2 is preferably, as before stated, formed from commercial wire, and its shape is given to it by swaging, rolling, or otherwise.

In assembling the cup A is passed over 90 the lower end of the pin and slipped without material friction up to the portion b and forced on to the portion b until it reaches the position shown in Fig. 1. The tapered portion d serves to guide the cup 95 from the smaller to the larger diameter. The parts fit so closely that a leak-tight metal to metal joint is formed between them. After the cup is in position the bottom of the portion b is upset or swaged or otherwise shaped to form a shoulder or shoulders E immediately beneath the cup, which 100

shoulders prevent the slipping down of the cup in use when the valve is under pressure.

Preferably during the same operation, or at a succeeding operation, as preferred, the 5 upper part of the portion *c* is also swaged to form shoulders *F*, such shoulders acting in the completed structure as a stop to limit the downward movement of the valve proper.

10 By the construction just described the parts may be assembled without distortion, since the jamming of the cup in place on the stem does not begin to take place until it approaches its final position. Consequently 15 there is much less risk of distortion of the parts. Furthermore, since the jamming action takes place only during a limited portion of the movement of the cup along the pin, the metal along the bore of the cup is 20 not worn or distorted so as to impair the tightness of the joint formed with the portion *b*. These considerations are of considerable importance in connection with a device which is of such small dimensions as 25 the parts in question, particularly in view of the fact that the parts are made of brass which is relatively soft and pliable in its nature.

Furthermore, in the operation of assembling there is no danger of injury or defacement of the seat *T* for the washer *B* on the valve proper. In prior operations wherein the valve proper was contracted by a longitudinal swaging operation by a tool 35 engaging the seat, the latter was liable to become out of true or defaced so that a perfectly smooth and true seat was difficult to obtain. In the present invention there is nothing to distort the seat and a perfectly 40 true bearing face for the washer is obtained so that the valve proper contacts evenly with the valve seat. This is important since it insures against leakage of the valve.

What we claim is:—

45 1. A device of the character described comprising a valve proper, a pin extending through said valve proper, said pin having a driven leak tight engagement with said valve proper, an upset shoulder on said pin below 50 said valve proper, and said pin having a portion of reduced diameter below said shoulder.

55 2. A device of the character described comprising a valve proper, a pin extending through said valve proper, said pin having a driven leak tight engagement with said valve proper, an upset shoulder on said pin below said valve proper, and said pin having a portion of reduced diameter below said 60 shoulder, and having a shoulder above said valve proper.

65 3. A device of the character described comprising a valve proper having a bore therethrough, a pin extending through said bore and having a portion contacting with

the latter of substantially the same diameter as said bore, the parts being united by a driven fit, an upset portion beneath said valve proper, and a reduced portion beneath said upset portion.

70

4. A device of the character described comprising a valve proper having a bore, a pin extending through said bore, said pin having a portion of substantially the same diameter as said bore, the parts being united 75 by a driven fit, a lower portion of smaller diameter, and an intermediate tapered portion, and said pin being upset immediately below said valve proper.

5. A device of the character described 80 comprising a valve proper, a pin extending through said valve proper, said pin having a leak-tight driven frictional contact with said valve proper and having a portion of reduced diameter below said valve proper.

85

6. A device of the character described comprising a valve proper, a pin extending through said valve proper and a distance below the same, said pin having a shoulder above said valve proper and above the lower 90 end of the pin, and said pin and valve proper having a driving fit whereby the valve proper is held in place by frictional contact.

7. The method of uniting a valve proper to a valve pin which consists in forming a 95 hole through the valve proper and driving the latter on the pin.

8. The method of uniting a valve proper to a valve pin which consists in forming a hole through the valve proper, forming a 100 pin with a portion of appropriate diameter to fit said hole with a driving fit, and a portion of less diameter between the first and the end of the pin, passing the valve proper over the portion of less diameter and driving 105 it on the portion of greater diameter.

9. The method of uniting a valve proper to a valve pin which consists in forming a hole through the valve proper and driving the latter on the pin, and forming a shoulder 110 on the pin below the valve proper.

10. The method of uniting a valve proper to a valve pin which consists in forming a hole through the valve proper, forming a pin with a portion of appropriate diameter to 115 fit said hole with a driving fit, and a portion of less diameter between the first and the end of the pin, passing the valve proper over the portion of less diameter and driving it on the portion of greater diameter, and forming a shoulder on the pin below the valve proper.

11. The method of uniting a valve proper to a valve pin which consists in forming a hole through the valve proper, forming a 125 pin with a portion of appropriate diameter to fit said hole with a driving fit and a portion of less diameter between the first and the end of the pin, and a taper between the two, passing the valve proper over the por- 130

tion of less diameter, and driving it on the portion of greater diameter.

12. A device of the character described comprising a valve proper, and a pin extending through said valve proper, the valve proper fitting the pin with a driving fit.

In witness whereof, we have hereunto

signed our names in the presence of two subscribing witnesses:
